W. E. ELLIS

TRAVELING BARREL PUMP

Filed Jan. 8, 1924

UNITED STATES PATENT OFFICE.

WARREN E. ELLIS, OF GRIDLEY, KANSAS, ASSIGNOR, BY DIRECT AND MESNE ASSIGNMENTS, TO ELLIS MANUFACTURING COMPANY, OF KANSAS CITY, KANSAS.

TRAVELING BARREL PUMP.

Application filed January 8, 1924. Serial No. 685,083.

To all whom it may concern:

Be it known that I, WARREN E. ELLIS, a citizen of the United States, residing at Gridley, in the county of Coffey and State 5 of Kansas, have invented certain new and useful Improvements in Traveling Barrel Pumps, of which the following is a specification.

This invention relates to a traveling barrel pump and particularly to the sliding connection at the lower end of the barrel upon the tubular anchored standard, and comprises an improvement upon the construction disclosed in my pending application 15 filed January 15, 1923, Serial Number 612,694.

In constructions of this character the space between the piston upon the anchored standard and the cap nut at the lower end 20 of the barrel forms a dead chamber in which more or less oil collects in the ordinary operation of the pump and if this body of oil enters the chamber with any velocity it carries sand in suspension which by contact 25 with the piston cups cuts the same so as to require frequent renewal. In order to permit free operation of the barrel upon the standard this cap nut must be spaced therefrom to permit a sliding movement without 30 binding, and such space allows the entrance of oil from the well tube which offers a resistance in the upward movement of the barrel when it is expelled and enters the dead chamber rapidly in the downward 35 movement during which the dead chamber is created.

To avoid these practical difficulties in operation the present invention has for an object to provide a valved connection at the 40 cap nut which will permit the free expulsion of the oil in the dead chamber in the upward movement of the barrel and practically close the space around the anchored standard in the downward movement of 45 said barrel.

A further object of the invention is to provide a novel and improved construction of cap nut having oil passages upon its interior adapted to be controlled by an annular check valve carried by the nut.

Other and further objects and advantages of the invention will be hereinafter set forth

and the novel features thereof defined by the appended claims.

In the drawing:

Figure 1 is a vertical section with parts broken away showing the pump assembled;

Figure 2 is a similar view upon an enlarged scale of the pumping elements;

Figure 3 is a detail section on line 3—3 of Figure 2;

Figure 4 is a similar view on the line 4—4 of Figure 2;

Figure 5 is a detail perspective of the cap nut; and

Figure 6 is a similar view of the annular check valve.

Like numerals refer to like parts throughout the several figures of the drawing.

The general construction and arrangement of the pumping elements is similar to that disclosed in my application before mentioned and comprises essentially a well tube 10 connected at its lower end to a casing 11 in which a tubular standard 12 is 75 suitably anchored as shown at 13. The upper portion of this tubular standard is provided with piston cups 14 and the arrangement thereof differs from that in the application mentioned in that all of the 80 cups are deflected downwardly and are secured in contact with the separators 15 by means of a lock nut 16. Above this nut the valve casing 17 is mounted upon the upper end of the standard and provided with a 85 check valve 18. Surrounding this piston and valve is a working barrel 19 which carries at its upper end a similar check valve 20 as usual in this type of pump.

At the lower end of the working barrel 90 19 a cap nut 21 is threaded therein and has a bearing upon the standard 12. The interior surface of this nut is formed with a series of oil passages 22 intermediate of the bearing surfaces 23 so as to permit the free 95 discharge of oil from the dead chamber 24 which exists between the nut and the valve at the upper end of the standard. For the purpose of controlling the flow of oil through these passages an annular check 100 valve 25 is provided and may be mounted upon the nut in any desired manner, for instance by means of the valve cage comprising the ring 26 separated from the nut by

- spacers 27 and open at its sides so as to permit the free insertion or removal of the annular check valve 25 which may be formed of any desired material, preferably of fiber.
- 5 The spacers 27 are of sufficient length to permit a reciprocatory motion of the annular check valve toward and from the base of the nut so that when in the lowered position as shown in Figure 3 the oil is free to be discharged from the dead chamber 24 during the upward movement of the barrel, while in the opposite or downward movement thereof this valve rises to the position shown in Figure 1 and closes the passages 22 so as 10 to practically prevent the entrance of oil into this chamber. This valve does not completely prevent the chamber from filling with oil but permits only a limited quantity to enter and prevents the oil entering with 15 a velocity which would carry with it sand or other material liable to injure the piston cups at the upper end of the standard with which the body of liquid is brought in contact during the ordinary movement of the 20 barrel.
- 25 The operation of the invention will be apparent from the foregoing description from which it will be seen that the construction presents a simple and efficient means for 30 controlling the entrance and discharge of oil from the dead chamber intermediate the barrel and anchored standard so as to secure the most efficient operation of the parts without resistance from any body of liquid 35 in such chamber and to prevent injury to the cups or other piston parts of the pump.
- Under some conditions the valve ring may be omitted as the passages in the cap nut permit the free flow of liquid and prevent 40 the formation of a dead chamber containing trapped liquid which will resist the free operation of the pump.
- 45 While the specific construction of the cap nut and its cooperating check valve has been shown and described, the invention is not limited thereto as changes and alterations may be made therein without departing from the spirit of the invention as defined by the following claims.
- 50 Having thus described my invention, what I claim as new and desire to secure by Letters Patent is:
- 55 1. In a pump, a tubular standard provided at its upper portion with a piston and valve, a working barrel surrounding said standard and piston, a cap nut at the lower end of said barrel, and a valve carried
- by said nut to restrict the passage of liquid between the barrel and standard in downward stroke of the former.
2. In a pump, a tubular standard provided at its upper portion with a piston and valve, a working barrel surrounding said standard and piston, a cap nut mounted in the lower end of said barrel and provided with passages upon its interior face, and a check valve carried by said nut and movable to close said passages in downward stroke of the barrel.
3. In a pump, a tubular standard provided at its upper portion with a piston and valve, a working barrel surrounding said standard and piston, a cap nut mounted in the lower end of said barrel and provided with passages upon its interior face, and an annular check valve carried by said nut and cooperating with the under face thereof to close said passages.
4. In a pump, a tubular standard provided at its upper portion with a piston and valve, a working barrel surrounding said standard and piston, a cap nut at the lower end of said barrel provided with interior passages surrounding said standard, a valve cage depending from said nut, and an annular check valve disposed in said cage to cooperate with the base of said nut.
5. In a pump, a tubular standard provided at its upper portion with a piston and valve, a working barrel surrounding said standard and piston, a nut disposed at the lower end of said barrel and provided with faces contacting with said standard and intermediate liquid passages upon its inner face, a valve cage comprising an annular ring connected to said nut by spacing lugs, and an annular check valve disposed within said ring to cooperate with the base of the nut.
6. In a pump, a tubular anchored standard provided with a valve at its upper portion, a series of cups mounted upon said standard and all depending downwardly, a lock nut for clamping said cups in position, a casing for said valve threaded upon the standard to engage said nut, a barrel surrounding said piston and standard, and a threaded cap nut mounted at the lower end of said barrel and provided with a valve disposed to restrict passage of liquid into the space between said nut and standard in the downward travel of the barrel.

In testimony whereof I affix my signature.
WARREN E. ELLIS.
